UNITED STATES PATENT OFFICE

151,662

DESIGN FOR A COMBINED STORAGE
CABINET AND BENCH

Frank F. Smead, Chicago, Ill., assignor to Shawnee Manufacturing Company, Chicago, Ill., a corporation of Illinois

Application May 9, 1947, Serial No. 138,947

Term of patent 14 years

(Cl. D15—8)

To all whom it may concern:

Be it known that I, Frank F. Smead, a citizen of the United States and a resident of Chicago, in the county of Cook and State of Illinois, have invented a new, original, and ornamental Design for a Combined Storage Cabinet and Bench, of which the following is a specification, reference being had to the accompanying drawings, forming a part thereof.

Fig. 1 of the drawings is a perspective view of a combined storage cabinet and bench, showing my new design; and

Fig. 2 is a perspective view of the same showing the top or cover portions in raised positions.

I claim:

The ornamental design for a combined storage cabinet and bench, as shown.

FRANK F. SMEAD,
